UNITED STATES PATENT OFFICE.

JOSEPH F. GILPIN, OF ANSONIA, CONNECTICUT, ASSIGNOR TO THE ANSONIA BRASS AND COPPER COMPANY, OF SAME PLACE.

MANUFACTURE OF INSULATED ELECTRIC CONDUCTORS.

SPECIFICATION forming part of Letters Patent No. 281,864, dated July 24, 1883.

Application filed April 14, 1883. (No model.)

To all whom it may concern:

Be it known that I, JOSEPH FREDERICK GILPIN, of Ansonia, in the county of New Haven and State of Connecticut, have invented 5 an Improvement in the Manufacture of Insulated Electric Conductors, of which the following is a specification.

Previous to my invention electric conductors had been covered with braided cords, 10 then dipped in paraffine and passed through a revolving head with spring-scrappers to rub off the surplus paraffine. Conductors had also been covered with braided threads, and paint applied between the layers of braided 15 covering, and also upon the outside of the braiding. In conductors in which paint is applied to the covering, the paint is liable to exist in lumps and irregular projections upon the surface, and the cords or threads are sometimes unduly elevated from the wire by the 20 paint beneath them. Besides this, the coils of wire are liable to adhere together when wound up, in consequence of too much paint remaining to allow the drying action to be uniform 25 and rapid.

My present improvement is to insure greater uniformity in the size of the fire-proof insulated electric conductor, to fill up all interstices in the braided covering, to prevent the 30 coils of wire adhering together when wound up, and to render the wire more smooth for handling when made use of.

I apply to the copper or other conducting-wire two or more layers of braided covering, 35 with paint or water-proof material between the layers of braid, as in the Patent No. 272,659, granted to Alfred A. Cowles, February 20, 1883, or in a similar manner, and I allow the covered material to set or partially dry, in order 40 that the threads may become impregnated with the paint and oil. In this condition the paint is slightly or partially plastic, and capable of being compressed, and the surface of the paint is harder than the paint which is 45 inclosed between the braided threads. While in this condition I subject the covered wire to a compressing and rubbing action, preferably

from spring-fingers *a a*, upon a tubular head, *b*, that is revolved rapidly by a wheel, *c*, and belt, while the conductor is drawn along gradually through the revolving head. This operation compresses the exterior threads into the paint that intervenes between the layers of braiding; it forces the partially-plastic paint into any unfilled interstices, so that the covering is made more thoroughly fire and water proof; the painted covering is rendered uniform, or nearly so, in size, and the surplus paint is rubbed off, so as to leave the surface smooth; but at the same time the fibrous 55 braiding is still left with a perfect covering of paint, to exclude the direct action of heat upon the fibrous material.

I am aware that in the Patent No. 272,660 rollers are shown to press and consolidate the 65 braid as it passes up out of the paint. In this condition the paint possesses very little adhesive power, and the braid is liable to expand. By my improvement the paint is allowed to partially dry, so that when the pressure is applied to the covering the paint and braiding 70 will be firmly consolidated, and remain in a firm, compact, and smooth condition.

I am also aware that braided wire has been immersed in melted paraffine and the surplus 75 material pressed off and the braiding polished by a revolving head having spring-fingers, as in Patent No. 176,978.

I claim as my invention—

The method herein specified of manufacturing insulated electric conductors, consisting 80 in applying two or more layers of braided covering, with paint between the layers, allowing the paint to partially dry, and then applying pressure to the surface to consolidate 85 the paint and the braiding, substantially as set forth.

Signed by me this 10th day of April, A. D. 1883.

JOS. F. GILPIN.
